UNITED STATES PATENT OFFICE.

HANS C. HANSEN, OF NEWTON, MASSACHUSETTS.

DEPTH-GAGE.

SPECIFICATION forming part of Letters Patent No. 740,646, dated October 6, 1903.

Application filed January 3, 1903. Serial No. 137,656. (No model.)

To all whom it may concern:

Be it known that I, HANS C. HANSEN, a citizen of the United States, residing at Newton, in the county of Middlesex and State of Massachusetts, have invented an Improvement in Depth-Gages, of which the following description, in connection with the accompanying drawings, is a specification, like characters on the drawings representing like parts.

10 This invention has for its object the production of a novel depth-gage adapted to, among other uses, detect any variations in parallelism between the face of a matrix and the bottom of a recess therein outlining a letter or character or for accurately testing for 15 trueness any recess in any article or thing.

My novel depth-gage comprises a block on which are mounted a sight-gage and a feeler, the latter entering the recess and by contact with the bottom thereof indicating at the sight-gage any variations in depth or any variations from parallelism between the bottom of the recess and the face of the matrix or other thing on which the sight-gage is mounted.

25 Figure 1 shows a matrix containing a recess and with my novel depth-gages sustained thereon. Fig. 2 is a longitudinal section of the same parts with the feeler occupying a position in another or deeper part of the recess.

30 Fig. 3 is a view like Fig. 2, but with the feeler in yet another part of the recess—namely, a shallower part; and Fig. 4 shows a modified form of gage.

The depth-gage comprises a body A, shown 35 as having feet a, preferably pointed, said feet being shown as sustained on the face of a matrix or block G. The body sustains a sight-gage, shown in Figs. 1 and 3 as comprising two levers b c, the lever b being shown as pivoted at b' on the body, while the lever c has its fulcrum at c' in an arm c², erected on the lever b. The lever c receives the lower end of the shank of a screw d, on which is movable a check-nut d'. The lever b has a hole in 45 which stands the upper end of a feeler e, which is held frictionally in the body A, as herein shown, by a friction device comprising a movable block f and a spring f'. The spring may be adjusted as to its strength by a screw f², 50 the feeler being so held that as the feet extending from the body are moved over the face of the matrix or block G the pointed end

of the feeler contacting with the bottom of the matrix will move the feeler freely vertically.

In Figs. 1 to 3 the matrix G is represented as having a recess g, that may form part of an intaglio letter or other recess the bottom of which it is desired to measure as to depth or as to parallelism with the face 2 of the matrix or block G.

Viewing Fig. 1, let it be supposed that the lower end of the feeler contacts with the bottom of the recess at a central point, and in this position the sight-gage is fully closed, the portion 3 of the lever c at such time contacting with the portion 4 of the lever b.

Fig. 2 shows the feeler as having been moved to the right from Fig. 1 down the inclined bottom of the recess, and in so doing the 7c weighted heavier right-hand end of the lever c, carrying the screw d and check-nut, by its contact with the upper end of the feeler is made to descend and follow closely the bottom of the recess. This movement of the 75 feeler results in moving the sight-gage c away from the member b thereof to leave a space 5, through which light may be seen, thus showing that the bottom of the recess from the point where the feeler contacts therewith in 80 Fig. 1 is out of parallelism with the face of the matrix.

Fig. 3 shows the feeler moved from the central position, Fig. 1, to the left into a shallower part of the recess. This position of the 85 body causes the upper end of the feeler to be raised, and the shorter arm of the lever c of the sight-gage is lifted to close the free ends of the two levers b c and lift the left-hand end of the lowermost lever b, as shown in Fig. 90 3, to form a space 6 between the under side of said lever and the upper side of the body A directly underneath.

It will be obvious that the sight-gage would be moved to indicate the light-spaces at the 95 end of members of the sight-gage were the bottom of the recess g exactly parallel with the bottom of the matrix and the face 2 of the matrix on which the feet of the body A rest were inclined with relation to the bottom 100 of the recess.

Fig. 4 shows a modification of my invention wherein the matrix is sustained in a ball B, mounted to be tipped freely between the

testing-surfaces 2 and 3 at the upper ends of side plates, as fully shown in application Serial No. 85,889, filed December 14, 1901.

The gage shown comprises the body D, having mounted upon it at d^2 a sight-gage d^3 . The sight-gage at the right of its pivot d^2 has, as provided for in Figs. 1 to 3, a screw and a check-nut, and the body D has feet d^4 d^5 , that stand on the testing-surfaces. The feeler e in Fig. 4 is similar to that shown in Figs. 1 to 3, and it will be supposed, viewing Fig. 4, that the bottom of the recess 10 is parallel with the face 2 of the matrix G.

This invention is not limited to the particular shape shown for the sight-gage or whether made of one or a plurality of parts, so long as it is capable of indicating a line of light between the parts of the gage when the bottom of the recess in which the feeler rests is not of the depth desired or is not parallel to the face by which the body of the gage is sustained.

Having described my invention, what I claim, and desire to secure by Letters Patent, 25 is—

1. A depth-gage comprising a body, a sight-gage pivoted thereto, a feeler movable by contact with the bottom of the recess to be measured at all points as to its depth, said feeler 30 operating the sight-gage and an adjusting-screw carried by the sight-gage and adapted to contact with the feeler.

2. A depth-gage for determining the parallelism between the face of a matrix and the bottom of a recess therein, comprising a body 35 having a sight-gage comprising a lever pivoted thereto, and a feeler to one side of the pivotal connection of the body and sight-gage to move the sight-gage on its pivot as the feeler is moved over the bottom surface of the recess, the said sight-gage carrying an adjusting-screw for contacting with the feeler.

3. A depth-gage for testing the trueness of a recess in an article, comprising a body movable over said article, a sight-gage carried 45 thereby, said sight-gage including two pivotally-connected levers, one of said levers being pivoted also to said body, and a feeler adapted to project into a recess and be moved over the bottom surface thereof, said feeler operating the levers of the sight-gage.

4. In a depth-gage, a body, a sight-gage carried by said body and comprising two piv-

oted levers, one of said levers being pivotally carried by the other of said levers, a feeler 55 adapted to act upon said levers, and a screw and check-nut carried by one of said levers and operative on said feeler.

5. In a depth-gage for testing the trueness of a recess in an article, the combination of 60 a body movable over the surface of the article to be tested, a feeler carried by said body and adapted to project into the recess in the said article, a lever pivoted to said body, a screw carried by said lever and contacting 65 with the top of the feeler, and means for securing the screw in adjusted position.

6. A depth-gage comprising a body having feet to sustain the body on the article having the recess to be measured or gaged, a 70 sight-gage pivotally mounted upon the body, a feeler to contact with the bottom of the recess in the article to move the sight-gage and an adjusting-screw carried by the sight-gage and adapted to contact with the feeler. 75

7. In a depth-gage for testing the trueness of a recess in an article, the combination of 80 a body, a sight-gage comprising two levers, one of said levers being pivoted to the body and the other of said levers being pivoted to the first-mentioned lever, a feeler carried by said body and adapted to operate said levers.

8. In a depth-gage for testing the trueness of a recess in an article, the combination of 85 a body, a lever pivotally mounted on said body, a second lever pivoted to the first of said levers, and a feeler operative on the second lever, said levers constituting a sight-gage.

9. In a depth-gage for testing the trueness 90 of a recess in an article, the combination of a body movable over the surface of the article to be tested, a lever pivotally mounted on said body, a second lever pivoted to the first-mentioned lever, and a feeler projecting 95 loosely through the first-mentioned lever and acting on the second lever, said levers constituting a sight-gage.

In testimony whereof I have signed my name to this specification in the presence of 100 two subscribing witnesses.

HANS C. HANSEN.
